UNITED STATES PATENT OFFICE.

GUY LEE HAMMOND, OF BRIDGEPORT, CONNECTICUT, ASSIGNOR TO ELECTRIC COMPOSITOR COMPANY, OF NEW YORK, N. Y., A CORPORATION OF NEW JERSEY.

ALINEMENT MECHANISM FOR LINE-CASTING MACHINES.

Specification of Letters Patent.

Patented Apr. 18, 1916.

1,179,524.

Application filed December 13, 1912, Serial No. 736,470. Renewed September 25, 1914. Serial No. 863,551.

To all whom it may concern:

Be it known that I, GUY L. HAMMOND, a citizen of the United States, residing at Bridgeport, in the county of Fairfield and State of Connecticut, have invented a certain new and useful Improvement in Aline- 5 ment Mechanism for Line-Casting Machines, of which the following is a full, clear, and exact description.

10 This is an improvement in machines which cast line long type slugs from assembled lines of matrices; and the object of this invention is to effect vertical alinement of the assembled matrices immediately prior 15 to their presentation to the mold.

The invention is shown as embodied in a machine in which the assembled matrix line is supported for presentation to the mold on the same elevator which subsequently carries 20 them up and delivers them to the matrix distributing mechanism.

The invention consists in the provision above the matrix line of an overhanging flange having a surface which occupies a 25 definite relation to the mold slot and which is adapted to be engaged by alinement surfaces on the matrices, and the employment of novel means by which, just prior to the final lock-up of the matrices, all of the 30 matrices are pushed up so as to bring the alinement surfaces with which they are provided into engagement with the alinement surface above them.

In the drawing, Figure 1 is a rear elevation of an elevator and associated mechanism embodying the invention—the matrix line on said elevator being sectioned, and parts of the elevator being broken away. Fig. 2 is a side elevation of the elevator and 35 40 a sectional view of some associated parts; and Fig. 3 is a sectional side elevation of the part of the elevator by which the matrix line is supported and alined.

Referring to the parts by letters, E represents the elevator which is to be moved vertically up and down by suitable means and is guided by suitable means, as for example, by two vertical guide rods F and F. The elevator is provided with a matrix supporting shelf e, which when the elevator is down, is in such position that a line of matrices may be pushed onto the same. During the casting operation, the matrix line is compressed laterally between a fixed abutment A

which is located adjacent to one end of the 55 elevator and an end clamp C. This much of the construction is old.

The shelf e has a slot e¹ extending down from its top and running from end to end. In this slot is an alining bar D which projects above the top surface of the shelf, this projecting part being in the form of a dovetailed rib d which enters the dovetailed notches m in the bottom of the matrices M. This particular dovetailed shape of the alining bar rib has a useful function in the machine, but is not essential to the particular invention which the appended claims define. This bar has two (more or less) inclined surfaces d¹, d², on its lower edge, and these are 70 for engagement with similar surfaces g¹, g², on the top of the slide G. This slide is located below the alining bar and in the same recess in the elevator shelf. This slide is movable endwise but the alining bar is not, 75 being held against such movement by horizontal pins H fixed to the elevator shelf and going through short vertical slots d³ in the alining bar. The alining bar is moved down against the slide G by the action of a spring 80 J which is connected with the alining bar at its upper end, and, passing through a hole in the slide, is connected at its lower end with a horizontal pin j which engages the bottom of the elevator shelf.

85 A stud K projects horizontally forward from the slide G through a horizontal slot in the elevator. This stud will be in such position that when the elevator descends, it will pass between the forked ends of an arm N, which is rigidly connected with another arm N¹ so as to form in effect a lever which is fulcrumed at n. This arm N¹ engages with a rotatable cam P and is held in such engagement by a spring S. When this cam 90 in rotating reaches a position such that the arm N¹ can drop into the depressed part of the cam, the spring S will so move the forked arm N, that it will move the slide G to the right, as shown in the drawing, and thereby through the action of the inclines g¹, g², d¹, d², on it and on the alining bar D referred to, will cause such alining bar to move up. In this upward movement, the upper edge of the alining bar will engage the 95 matrices and push them up until their top edges which serve as alining surfaces engage the overhanging alinement flange e² of

the elevator. This accurately alines the matrices with respect to the mold W and the pot nozzle R, because the elevator is at rest in a definite position with respect to these parts. When the elevator is lowered, it rests upon carefully adjusted supports T.

Having described my invention, I claim:

1. In a line casting machine, the combination of a shelf which is adapted for supporting a line of assembled matrices and has a longitudinal recess in its top surface, a horizontal alining bar which is seated in said recess and is movable vertically only therein, an alinement flange located in a position above said shelf such that when matrices resting on said shelf are moved up by upward pressure from the alining bar said matrices will be moved into engagement with said alinement flange, and means for pressure bar longitudinally.

2. In a line casting machine, the combination of a vertically movable elevator provided with a horizontal shelf which is adapted for supporting a line of assembled matrices and has a longitudinal recess in its top surface, a horizontal alining bar which is seated in said recess and is movable vertically only therein, an alinement flange fixed to said elevator and located in a position above said shelf such that when matrices resting on the shelf are moved up by upward pressure from the alining bar said matrices will be moved into engagement with said alinement flange, and means for moving said alining bar up.

3. In a line casting machine, the combination of a vertically movable elevator provided with a horizontal shelf which is adapted for supporting a line of assembled matrices and has a longitudinal recess in its top surface, a horizontal alining bar which is seated in said recess and is movable vertically only therein, an alinement flange fixed to said elevator and located in a position above said shelf such that when matrices resting on the shelf are moved up by upward pressure from alining bar, said matrices will be moved into engagement with said alinement flange, a train of mechanism for moving said alinement bar up, which mechanism includes parts movably mounted on the elevator, and other parts movably supported on the fixed framework of the machine, said parts being constructed and arranged to be brought into cooperative relation by the descent of the elevator to its normal resting position.

4. In a line casting machine, the combination of a shelf which is adapted for supporting a line of assembled matrices and has a longitudinal recess in its top surface, a horizontal alining bar which is seated in said recess and is movable vertically only therein and has inclines on its lower face, a longitudinally movable slide seated in said re-

cess below said alinement bar and having on its top surface inclines which engage with the inclines on the alinement bar, an alinement flange located in a position above said shelf such that when matrices resting on said shelf are moved up by upward pressure from the alinement bar, said matrices will be moved into engagement with said alinement flange, and means for moving said pressure bar longitudinally.

5. In a line casting machine, the combination of a shelf which is adapted for supporting a line of assembled matrices and has a longitudinal recess in its top surface, a horizontal alining bar which is seated in said recess and is movable vertically only therein and has inclines on its lower face, a longitudinally movable slide seated in said recess below said alinement bar and having on its top surface inclines which engage with the inclines on the alinement bar, an alinement flange located in a position above said shelf such that when matrices resting on said shelf are moved up by upward pressure from the alinement bar said matrices will be moved into engagement with said alinement flange, means for moving said slide longitudinally, and a spring acting to draw said alinement bar down.

6. In a line casting machine, the combination of a shelf which is adapted for supporting a line of assembled matrices and has a longitudinal recess in its top surface, a horizontal alinement bar which is seated in said recess and is movable vertically only therein and has inclines on its lower face, a longitudinally movable slide seated in said recess below said alinement bar and having on its top surface inclines which engage with the inclines on the alinement bar, an alinement flange located in a position above said shelf such that when matrices resting on said shelf are moved up by upward pressure from the alinement bar, said matrices will be moved into engagement with said alinement flange, a stud carried by said slide, a lever engaging said stud, and means for rocking said lever.

7. In a line casting machine, the combination of a vertically movable elevator having a shelf which is adapted for supporting a line of movable matrices and has a longitudinal recess in its top surface, a horizontal alining bar which is seated in said recess and is movable vertically therein and has inclines on its lower face, a longitudinally movable slide also located in said recess but below said alinement bar and having inclines for engagement with the inclines on the alinement bar, an alinement flange fixed to the elevator and located in a position above the shelf such that when matrices resting on the shelf are moved up by upward pressure from the alinement bar said matrices will be moved into engagement with said aline-

ment flange, a horizontal stud fixed to said longitudinally movable slide, an upwardly projecting lever having a fork in its upper end into which said stud will move when the elevator descends to its normal resting position, and means for rocking said lever.

8. In a line casting machine, the combination of a vertically movable elevator having a shelf which is adapted for supporting 10 a line of movable matrices and has a longitudinal recess in its top surface, a horizontal alinement bar which is seated in said recess and is movable vertically therein and has inclines on its lower face, a longitudinally 15 movable slide also located in said recess but below said alinement bar and having inclines for engagement with the inclines on the alinement bar, an alinement flange fixed to the elevator and located in

a position above the shelf such that when 20 matrices resting on the shelf are moved up by upward pressure from the alinement bar said matrices will be moved into engagement with said alinement flange, a horizontal stud fixed to said longitudinally movable slide, an upwardly projecting lever having a fork in its upper end into which said stud will move when the elevator descends to its normal resting position, a lever arm 25 fixed to said forked lever, and a cam engaging therewith.

In testimony whereof, I hereunto affix my signature in the presence of two witnesses.

GUY LEE HAMMOND.
